UNITED STATES PATENT OFFICE.

LEONARD R. CARLEY, OF WATERBURY, CONNECTICUT.

BUTTON-ATTACHING MECHANISM.

1,178,904.

Specification of Letters Patent. Patented Apr. 11, 1916.

Application filed December 27, 1913. Serial No. 808,928.

To all whom it may concern:

Be it known that I, LEONARD R. CARLEY, a subject of the King of Great Britain and Ireland, residing at Waterbury, in the county of New Haven and State of Connecticut, have invented certain new and useful Improvements in Button-Attaching Mechanism, of which the following is a specification, reference being had therein to the accompanying drawings.

The invention relates to machines for attaching buttons or similar articles to a garment or other fabric, and more particularly to that type in which the article is attached by a metallic fastener.

It is the object of the invention to insure a positive operation of the machine, avoiding danger of false registration of the attaching shank with the button, or the bending of the shank during the penetration of the same through the fabric.

To this end the invention consists in the construction as hereinafter set forth.

In the drawings: Figure 1 is a side elevation of a button attaching machine to which my improvements are applied; Fig. 2 is a front elevation of the attachment mechanism; Fig. 3 is a longitudinal section therethrough; Fig. 4 is a plan view of the jaws; and Figs. 5, 6 and 7 are diagrams illustrating the operation.

The machine as illustrated is designed to use double pronged attachment shanks or staples, but it is obvious that the same mechanism could be used with a single prong shank.

The drawings also show a specific construction of button which is provided with a cross bar around which the prongs are hooked or clenched, but this also is not essential to the invention.

A is the frame of the button attaching machine; B is the reciprocating plunger for clenching the button shanks; and C is the stationary support or anvil, preferably slightly recessed at C' to receive the head of the fastener.

D and D' are jaws above the anvil and projecting from opposite sides of the same, said jaws being provided with grooves E for receiving the prongs of the fastener. The jaws D and D' are carried by arms F and F', which embrace the anvil D and at their lower ends are pivotally connected to each other by a link G. This link is also in engagement with a lever H, which is ful-

crumed upon the frame and is actuated through the medium of a compound lever I from a cam J, an anti-friction roll K at the end of the lever I bearing against said cam, 60 and a spring L yieldably pressing the lever in the opposite direction.

The jaws D and D' are normally so arranged as to engage with the upper ends of the fastener prongs when the latter is supported upon the anvil C. Any suitable mechanism (not shown) may be employed for engaging the fasteners with the grooves E in the jaws, but as illustrated in Fig. 4, the jaws are provided with a tapering entrance slot E' which will guide the prongs into the grooves. When the prongs of the fastener are thus engaged, a button, as indicated at M, is placed upon the plunger B, while the cloth or fabric M' is arranged between the button and the prongs of the fastener, as indicated in Fig. 5. The plunger B is then depressed, and simultaneously the jaws D and D' are moved downward so as to permit the points of the prongs to penetrate 80 the cloth, but at the same time to guide and support them during this movement. After the points penetrate the cloth and embrace the cross-bar M² of the button, they will be turned by the concave surface B' of the plunger B, as shown in Fig. 6. The jaws D and D' are then laterally withdrawn and the plunger completely depressed, as shown in Fig. 7.

For effecting the movement just described, the arms F and F', which carry the jaws D and D', are provided with suitably cammed faces coöoperating with cammed faces on the anvil C and complementary cammed members N and N' on opposite sides thereof. In the initial position shown in Fig. 5, the cams N and N' permit a slight spreading of the jaws sufficient for the introduction of the prong fastener into the grooves E. When, however, the arms F and F' are drawn downward by the operation of the cam J and levers I and H, projecting portions O upon the arms F and F' engaging with portions P of the cam members N and N', will hold the jaws D 105 and D' in closed position, as shown in Fig. 2. The jaws remain in this closed position during their further depression and the penetration of the cloth by the sharp ends of the prongs until the position shown in Fig. 6 is reached, in which position the ends of the prongs have been turned, as indi-

cated. A further downward movement of the arms F and F' will bring the cam faces P' on said arms into engagement with the cam faces Q on the anvil C, which, by their engagement, will cause the spreading of said arms and the lateral withdrawal of the jaws, as shown in Fig. 7. This movement is permitted by the cam members N and N', which are cut away at R to form recesses. The plunger B continues its downward movement during the operation just described, and consequently completes the clenching of the prongs and the securing of the button to the fabric. The plunger B and the arms F and F' are then returned to their initial positions ready for a repetition of the operation.

From the description just given, it will be understood that the prongs of the fastener are supported and guided until they are completely engaged with the button, thereby avoiding danger of misplacement by the resistance of the cloth through which they are passed. It is obvious that the same result could be obtained with a fastener having but a single prong.

What I claim as my invention is:

1. The combination with relatively movable members for respectively holding a button and a fastener upon opposite sides of the garment, of means surrounding the shank of the fastener for positively holding said fastener in registration with the eye of the button during the relative movement thereof, and means for subsequently withdrawing said holding means from said fastener.

2. The combination with relatively movable members for respectively holding the button and a fastener upon opposite sides of the garment, of means engaging the shank of the fastener intermediate its ends and positively guiding and holding the same in registration with the eye of the button during the relative movement thereof, and means for withdrawing said engaging means near the end of said relative movement.

3. The combination with relatively movable members for respectively holding a button and a fastener upon opposite sides of the garment, of means engaging the shank of the fastener intermediate its ends and positively guiding the same in registration with the eye of the button during the relative movement, means for shifting the engagement of said guide toward the rear of said shank during the movement of the latter through the garment, and means for finally withdrawing said guide from said shank to permit the tightening between said button and fastener.

4. The combination with relatively movable members for respectively holding a button and a fastener having a pointed

shank, of means for engaging said shank near the point end thereof and positively holding the same in registration with the eye of the button during the relative movement of the parts, means for causing said guide to travel toward the rear of the shank during the movement of said fastener into engagement with the eye of the button, and means for withdrawing said guide from between the fastener and button to permit the tightening thereof.

5. The combination with relatively movable members for respectively holding a button and a fastener having a pointed shank upon opposite sides of the garment, of means for engaging said shank near the point end thereof and positively guiding the same in registration with the eye of the button during the initial relative movement, means for shifting the engagement of said guide toward the rear of the shank during the continued relative movement of the button and fastener, and means for finally withdrawing said guide from between the fastener and button to permit the tightening thereof.

6. The combination with relatively movable members for respectively holding a button and a fastener having a pointed shank on opposite sides of the garment, of a positive guide for said shank holding the same in registration with the eye of the button comprising a pair of oppositely moving jaws, means for closing said jaws around said shank adjacent to the point thereof during the initial relative movement, means for retaining said jaws in engagement with said shank and causing the traveling of the same toward the rear during the penetration of the garment and initial engagement with the eye, and means for opening and withdrawing said jaws during the final relative movement of the button and fastener to permit tightening.

7. The combination with relatively movable members for respectively holding a button and a fastener having a pointed shank, of a pair of oppositely moving jaws together forming a grooved guide bearing for said shank near the point end thereof and for positively holding the same in registration with the eye of the button, means for maintaining the engagement of the guide during the continued relative movement of parts but permitting it to travel toward the rear of the shank, and means for finally withdrawing the jaws to permit the clenching of the fastener.

8. The combination with relatively movable members for respectively holding a button and a fastener having a pointed shank, of a guide comprising a pair of oppositely movable jaws embracing the holder for the fastener, means for moving said jaws relative to said holder for the fastener

during the relative movement of the button holder, and cams operating during the movement of said jaws to close the same in engagement with the shank near the point 5 end thereof to maintain said engagement while traveling toward the rear of the shank and then to release said engagement and separate the jaws during the final relative movement of the button and fastener 10 holders.

9. The combination with a plunger member forming a button holder and a member therebeneath on which a fastener is supported, of a pair of positively guided jaws 15 embracing said fastener member, means for moving said jaws in the plane of movement of said plunger toward said fastener supporting member, and cams operating during said movement for causing first, the 20 closing of said jaws about the shank of the fastener near the point end thereof, then maintaining the jaws closed until the same are near the rear end of the shank and finally separating the jaws to withdraw the 25 same from about the shank.

10. In a button attaching machine a holder for a fastener having a shank, including means for positively engaging said shank, and means for disengaging said 30 shank-engaging means from the shank by a movement parallel with the shank.

11. In a button attaching machine a holder for a fastener having a shank, said holder positively engaging the shank intermediate its ends, means for preventing disengagement of the holder from the shank during a portion of the operation, and means for subsequently disengaging the 35 holder from the shank by a movement parallel with the shank.

12. In a button attaching machine a holder for a fastener having a shank, means for engaging said holder with the shank intermediate its ends, means for preventing 40 disengagement of the holder from the shank during a portion of the operation, and means for subsequently disengaging the holder from the shank moving said holder laterally from said shank.

50 13. In a button attaching machine a holder for a fastener having a shank comprising jaws on opposite sides of the shank,

means for causing said jaws to laterally engage said shank intermediate its ends, and means for positively holding the jaws from 55 separating during the engaging operation.

14. In a button attaching machine a holder for a fastener having a shank comprising jaws on opposite sides of the shank, means for causing said jaws to laterally engage said shank, means for positively holding the jaws from separating during the 60 engaging operation, and means for subsequently laterally disengaging the jaws from the shank. 65

15. In a button attaching machine, a holder for a fastener having a shank, comprising jaws on opposite sides of the shank, means for causing said jaws to move substantially parallel with said shank, means 70 for positively holding said jaws from separating during a portion of the movement, and means for subsequently withdrawing the jaws. 75

16. In a button attaching mechanism a combination of relatively movable members having coöperating cams thereon, one of said members comprising a holder for a fastener having a shank, said cams causing the engagement and disengagement of said 80 holder with said shank.

17. In a button attaching machine, relatively movable members for respectively holding a button and a fastener having a shank, and means surrounding the shank 85 for positively holding the same in registration with the eye of the button during the relative movement of the members.

18. The combination with relatively movable members for holding a button and a 90 fastener upon opposite sides of the garment, said fastener having a pointed shank for piercing the garment, of means positively engaging said shank for positively guiding and holding said fastener in registration with the eye of the button during 95 the relative movement thereof.

In testimony whereof I affix my signature in presence of two witnesses.

LEONARD R. CARLEY.
